UNITED STATES PATENT OFFICE.

ALBERT V. LOCKE, OF LAKEPORT, NEW HAMPSHIRE, ASSIGNOR OF TWO-THIRDS TO FRED L. PACKARD, OF BROCKTON, MASSACHUSETTS, AND HENRY S. SLATER, OF BROOKLINE, MASSACHUSETTS.

CARTON.

SPECIFICATION forming part of Letters Patent No. 700,953, dated May 27, 1902.

Application filed August 22, 1901. Serial No. 72,905. (No model.)

To all whom it may concern:

Be it known that I, ALBERT V. LOCKE, a citizen of the United States, residing at Lakeport, in the county of Belknap and State of New Hampshire, have invented certain new and useful Improvements in Cartons; and I do hereby declare the following to be a full, clear, and exact description of the invention, such as will enable others skilled in the art to which it appertains to make and use the same.

This invention relates to an improvement in combined storage and display cartons; and it is embodied in the construction and arrangement of parts presently to be described, and defined in the claims.

The invention is designed more particularly for the storage and display of shoes, although its useful application is not necessarily limited to such specific use.

The general object of the invention is the provision of a carton which permits avoiding the necessity of using the ordinary or usual separate cover, which will comprise two substantially equal sections, each of which is fashioned and proportioned to receive a shoe, and which when closed will in all essential respects constitute practically a dust-tight receptacle in shape and size that of the conventional shoe-box, but when open will constitute two separate boxes or trays of equal size.

In the accompanying drawings I have shown a structure embodying the invention, but desire it understood that modifications thereof can be made without departing from the nature and principle thereof.

Figure 1 is a perspective view showing the carton closed. Fig. 2 is a perspective view showing the box open, and Figs. 3 and 4 are detail views of the fastener and its connection.

A B designate, respectively, two rectangular sections or receptacles of equal size and dimension and each when the carton is intended for shoes is of a size to contain a single shoe. These sections are united along one edge by a flexible hinge C in a well-known manner. On the inner joint of the section A is permanently secured a stiff strip D, which projects beyond the edge of the section on its ends and side opposite the hinge. This pro-

jecting strip telescopes into the companion section, closely fitting therein and forming a closed joint between the sections when the carton is in a closed condition. The carton thus described when closed constitutes a box in size that of the ordinary shoe-box or approximately such, and, as shown in Fig. 1, the label c is secured across the ends of the two sections. In this connection the label serves to secure the parts together, but would readily be disrupted or torn by any twisting or distortion of the two sections relative to each other. This liability is largely overcome by the overlapping flange D, which also serves as a closure for the joint, preventing the ingress of dust.

To fasten the two sections closed and so in an economical manner, I provide a fastener F, consisting conveniently of a single piece of wire bent into substantially V shape, having the central or connection portion bent into a loop t, standing at substantially a right angle to the other portion. The free ends of the fastener are projected through the sides of the section A at a point immediately below the strip D, and its ends t' are bent up to come in contact with the strip, as shown in Fig. 3. This arrangement prevents the fastener from being drawn out of or tearing the material forming the section A, but permits a slight pivotal movement of the fastener. In the section B is formed an opening b, into which the hook end of the fastener projects, thus securing the sections together. The fastener by its peculiar construction and arrangement forms but a small projection on the top of the carton when the latter is closed.

Having thus described the invention, what is claimed as new, and desired to be secured by Letters Patent, is—

1. As an article of manufacture, a carton consisting of two parts, A, B, of equal size, a hinged connection between the parts, a strip, D, fixed to one of the parts projecting beyond the same and arranged to enter the companion part, and a fastener for the two parts consisting of a hooked member having its ends t' projecting through the part A immediately below the strip D, substantially as described.

2. As an article of manufacture, a carton comprising two parts adapted to fit the one upon the other, a strip on the edge of one part projecting beyond the same, and a fastener for securing the parts together comprising a substantially V-shaped member having its apex offset and its free ends inserted through one of the parts of the carton and bent down upon the inner face of the same, the other part

of the carton having an opening therein for 10 the reception of the offset portion of the fastener, substantially as described.

In testimony whereof I affix my signature in presence of two witnesses.

ALBERT V. LOCKE.
